9 Claims. (Cl. 250—27.5)

1

This invention is concerned with electron discharge tubes and methods of mounting same in relation to casings which can be used for cooling parts of the tubes by air streams, and furthermore is concerned with the relationship of the input and output circuits of discharge tubes particularly when operated with very short wave lengths or ultra high frequencies.

The design of electron discharge tubes and the associated circuits for operation on wave lengths below 1 metre, for example, presents certain special difficulties. One of these lies in the fact that circuits for use with a tube for both input and output purposes in general consist of an enclosed metallic structure or casing such as that of the well known shielded concentric quarter wave line. The radiation losses in such a transmission line circuit become very considerable if the continuity of its outer conductor or shield is broken. It is not easy to devise a construction for an electron discharge tube such as a deflection valve which enables an electron beam or stream inside the evacuated envelope of the tube to be deflected or modulated by the field of an input circuit, and which enables such an electron beam to give energy to an output circuit which is necessarily external to the tube, while at the same time maintaining a low loss in the input and output circuits. This difficulty is aggravated by the necessity of providing tuning adjustment mechanism for the circuits. Possibly, however, the greatest complication arises because, in addition, some means has to be employed to remove excess heat during operation from the assembly of the discharge tube and its circuits. This is particularly necessary in the case of tubes provided with massive copper electrodes sealed into glass envelopes. Such electrodes are often necessary in discharge tubes operating with ultra high frequencies in order to provide a low loss connection in the external circuit connected to the electrodes of the tube. The temperature of such copper electrodes must not be allowed to rise to a point at which the joints between the copper and glass may be damaged or gas evolved from the internal parts of the tube. Water cooling of the appropriate parts is, of course, extremely effective but is most inconvenient and expensive.

The chief object of the invention is to provide a method of construction for a valve and its circuits to operate at ultra high frequencies and which are electrically efficient and are readily and efficiently cooled during operation.

According to the present invention, an electron discharge tube is mounted on a supporting platform and a casing forming part of a shielded circuit connected to the discharge tube, such as the output circuit, or forming part of the input and output circuits, is also carried by the said

2

platform and surrounds the tube, while means are provided for drawing a stream of air through the casing to serve as a cooling medium for parts of the tube which during operation would otherwise become overheated. The platform may constitute a partition in the said casing which it divides electrically and mechanically into two parts which actually form parts of the input and output circuits of the discharge tube. The supporting platform may also serve for connecting an electrode in the discharge tube to its external circuit, and in fact, an electrode constituted by a transverse plate sealed to the envelope of the discharge tube and extending outside the envelope. In some cases, for example, in the discharge tube set forth in patent application Serial No. 409,585, filed September 4, 1941, such an electrode has to be maintained at a different direct potential from the external circuit which may be at a higher potential, and then the platform, while mechanically supporting the casing, may be electrically connected to it through the dielectric of a condenser.

This arrangement enables the air stream provided for cooling purposes to be directed on to the said transverse plate electrode, and an anode or output electrode may also be extended to the outside of the envelope and cooled by direct contact with the air stream. Generally speaking, the air stream may be directed into the neighbourhood of any parts which require especially effective cooling. In particular, when the casing is divided into two parts by the partition, streams of air may be drawn through the two parts and at one end directed towards an output electrode, and at the other end towards lead-in conductors of other electrodes. The transverse plate electrode may be furnished with external heat radiating surfaces or fins which are cooled by the stream of air.

As regards the tuning mechanisms, these may be mounted on those parts of the casing which form part of the external circuits and may be arranged for the adjustment of the dimensions of the casing necessary for tuning the circuits to the required frequencies. For example, at least one end of the casing may consist of two telescoping members which may be extended or contracted by the tuning mechanism so that for tuning purposes the effective length of the end of the casing is changed.

In order that the invention may be clearly understood and readily carried into effect, some forms of construction in accordance therewith will now be described by way of example with reference to the accompanying drawings, in which:

Figure 1 is a central section showing the mounting of the tube within a casing forming part of the output circuit;

Figure 2 is a fragmentary section showing in detail the method of securing the tube in its mounting;

Figure 3 is a longitudinal section showing another type of tube in which the casing forms part of the input and output circuits;

Figure 4 is a longitudinal section seen at right-angles to Figure 3 of the end of the enclosing casing containing the tuning arrangements for the input circuit;

Figure 5 is a general diagrammatic view showing two such tubes in their casings mounted on a deck forming the top of a cabinet; while

Figure 6 is a general view showing the mounting of a tube as shown in Figure 1.

Referring to Figures 1 and 2, the anode end of a tube is shown of the construction set forth in patent application Serial No. 409,585, filed September 4, 1941, or in Figures 1 to 11 of the drawings accompanying the specification of patent application Serial No. 409,589, filed September 4, 1941. The upper part of the envelope E is shown with the output target or anode T fused into a re-entrant seal, while the sub-anode SA is sealed to the two parts of the glass envelope E. The tube is mounted by bedding the sub-anode SA on to a seating of a brass ring 30 with a thin silver ring 31 interposed to make good contact. The sub-anode SA is pressed on to the seating by three equally spaced screws 32 screwed radially into the ring 30, and formed with conical points which press the sub-anode SA on to the seating, as shown in detail in Figure 2. A voltage of 1500 volts for the sub-anode is applied to a ring 30a which is in metallic contact with the ring 30 so that the rings 30, 30a constitute a metal platform support for the discharge tube. The terminal of the target T consists of a rod 12 which is actually tubular as shown, and is perforated near its lower end for cooling purposes. For this purpose, air is forced into the upper end of the rod 12 and passes out through the perforations at the bottom into contact with the target T and into the inside of a telescoping casing 33, 37 which forms part of the output circuit. It passes out of this casing through vent holes 40a in the upper wall 40 of the casing. The rod 12 is screwed into the target T so that both it and the discharge tube, which is a deflection valve, are fixed relatively to the brass ring 30. The part 33 of the casing which is of sheet metal and open at the top, is soldered to another brass ring 34 secured by screws 35 to a third brass ring 36. A sheet metal cap 37, which also has its lower end split at 38, telescopes into the part 33 and has a tubular sleeve 39 soldered into the end wall 40. The sleeve 39 is capable of sliding on the rod 12 so that the latter, the sleeve 39, the end wall 40, the cap 37, the sheet metal casing 33, and the brass rings 34 and 36, are all subjected to the voltage of the target T, which in this example is 2500 volts. Therefore, these parts have to be insulated from the brass ring 30a which, as already mentioned, is at the sub-anode voltage of 1500 volts. For this purpose, a sheet of mica 41 about 0.01 inch in thickness is interposed between the brass rings 30a and 36, but these rings are mechanically secured together by screws 42 which pass through the ring 36 and pass through large holes in the ring 30a and screw into nuts 43 which are insulated from the brass ring 30a by mica washers 44. In this way, the parts subjected to the two different voltages are insulated from one another and the sheet of mica 41 forms the dielectric of a condenser through which the two sets of parts are

connected. This assembly, as a whole, will be recognised as a concentric line type of tuned circuit. To reduce losses while enabling sufficient mechanical strength to be maintained, the parts 33, 37, 40, and the rings 30, 30a, 34 and 36, should be made of brass and be silver-plated. Good contact surfaces must be maintained.

It is arranged that the metal cap 37 can slide for tuning purposes relatively to the sheet metal casing 33 and the brass rings which are fixed to the sub-anode SA, and to enable this to be done, a sleeve 45 is secured by grub screws 46 to the sleeve 39 and is provided with a right-handed screw-thread 47 on its outer surface. This screw-thread engages an internal right-handed thread in a nut 48 fixed within an ebonite adjusting disc 49. On the other side of this disc there is a nut 50 which has an internal left-handed screw-thread engaged by a threaded sleeve 51 fixed by grub screws 52 to the upper part of the rod 12. Now if the ebonite disc 49 is rotated so as to cause the nut 50 to ride up on the screw-thread of the sleeve 51, owing to the fact that the sleeves 51 and 45 have threads of opposite hand, the sleeve 45 will be drawn upwards into the nut 48 at double the rate if the pitches of the two screw-threads are the same. Thus, the sleeve 39 and the sheet metal cap 37 are drawn up relatively to the metal casing 33. Similarly, if the disc 49 is rotated in the opposite direction, the cap 37 is forced down into the casing 33, and in this way tuning of the concentric conductors 12 and 33, 37 is effected. The loop 15 is a pick-up loop connected to conductors 53 for connection to a di-pole transmitting aerial. The loop 54 is a tuning loop connected directly to a small lamp 55 which, by its brilliance, indicates the tuning point.

In Figures 3 to 5, the mounting of tubes is shown, the envelope of each of which has a central copper section between two end sections of glass, as shown in Figures 12 to 21 of the drawings accompanying patent application Serial No. 409,589 referred to above. The output circuit arrangements making use of a concentric conductor system shown in Figure 3, includes a sheet metal casing 33 with a cap 37 and end wall 40, to the latter of which is secured the sleeve 39 which is caused to slide over the tubular conductor 12 which is screwed into the target electrode T. It will be noticed that in this case the target electrode is not sealed into a re-entrant seal and is more accessible to the cooling air which enters through apertures 110 and leaves through the outlet pipes 111.

The tube is secured in this case to a deck 83, and for this purpose, while the sub-anode SA is bedded on to a plate 30 which again forms a metal platform support separated from the parts metallically connected to the target electrode T by a sheet of mica 41 forming the dielectric of a condenser as described above with reference to Figures 1 and 2, the central copper part E' of the envelope of the discharge tube has a system of cooling fins forced on to it. This system consists of an inner ring 84 of the cross-section shown in Figure 3, and a series of radial cooling fins 85 extending from it. The outer surface of the copper tube E' and the inner surface of the ring 84 have a slight taper. The surfaces are cleaned and the ring 84 pushed on to the tube E' to make good thermal contact with it. At the lower outer edge of the fins 85, there is an outwardly-extending ring or flange 86 which is secured by screws 87 to the deck 83.

The tuned input circuit also consists of a shielded two-wire adjustable transmission line. Its shielded casing provides a means of applying air cooling and acts as a support for the lead-in wires. Thus, the ring 84 is extended downwards at 88 beyond the fins 85, and this downward extension receives the cylindrical shield 89 of the input circuit which consists of metal tubing fixed in position by screws 90. The lead-in conductors d^1, d^2 to the parts D^1, D^2 of the deflection cylinder are connected by short lengths of braided flexible conductor 91 to a pair of Lecher wires 92. For tuning purposes a piston or plunger 93 is provided which can slide in the casing 89 and forms the adjustable bridge-piece between the Lecher wires 92. In order to facilitate assembly, the casing 89 has a flanged joint at 94. The piston 93 is adjusted by a handle 95 on the lower end of a screw-threaded rod 96 which, as seen in Figure 5, is taken out through insulating bushings 97 mounted in the lower wall 98 of the casing or cabinet 99 which encloses the pair of tubes shown in that figure. The rod 96 screws in a nut 100 forming part of the bottom wall of the casing 89, and the rod 96 extends through the wall of the piston 93 in which it can turn but is prevented from sliding relatively to the piston by a pair of nuts 101 pinned to it. The input supply is brought to it by a pair of shielded conductors 102 which feed into a loop 103 carried in the wall of the piston 93, by an insulated thimble 104. All high frequency tuning conductors may be of brass and should be silver-plated to reduce losses.

Cooling is partially effected by a relatively slow current of air indicated by the arrows 105, which flows in radially between the fins 85 and through the annular hole 106 in the deck 83, as seen in Figure 3. In addition to this, the lower seals for the lead-in wires of the valve and the target seal are cooled by higher speed air currents. It has already been mentioned that for the latter air is drawn in as indicated by the arrows 110 in the outlet circuit casing 33 and is taken away through two outlet pipes 111 which may be of glass and pass through the end wall 48 of the cap 37. For the lower seals the air passes in through inclined glass tubes 107 which are optional but which, when provided, prevent this air from coming into contact with the fins 85 and thus becoming heated. The high speed air current follows the arrows 108 into contact with the lower seals and is taken away laterally through the casing 89 by way of an outlet pipe 109.

The arrangement is capable of modification by altering the tubes and apertures so as to direct the air to desired parts of the assembly. The outlet pipes may be of any material not having high electrical losses. A by-pass condenser is shown as formed of a copper band 112 encircling the input casing 89 and separated from it by a sleeve of mica 113. The lead-in conductors may be by-passed to the case with respect to ultra high frequency currents, by the method illustrated, by way of example, in the drawings by the conductor 9 which is brought out through a bushing 114 in the side of the casing 89 and is connected by a wire 115 to the copper band 112 of the condenser. A piece of mica (not shown) may be used to keep dust out of the condenser 36, 70 30 and the entering air may be cleaned or filtered in any convenient way.

In the complete arrangement shown in Figure 5, two tubes enclosed in casings, as shown in Figures 3 and 4, are mounted on a deck 83 which

forms the top of a cabinet 99. The lower outlet pipes 109 from the tubular casings 89 and the upper outlet pipes 111 are both brought into an outlet manifold 116 from which the heated air is withdrawn by a fan at 117 driven by a small electric motor 118. The cabinet 99 forms a passage of large cross-section for the slow current of cooling air indicated by the arrows 105. This air is drawn out of the cabinet by a fan 119 also driven by an electric motor 120.

In Figure 6 a complete mounting is shown for a discharge tube having an envelope which apart from the sub-anode SA is made entirely of glass, as illustrated in Figs. 1 to 11 of the drawings of patent application Serial No. 409,589 mentioned above, and with an output circuit as shown in Figure 1. Again, it is mounted on a deck 83 forming the top of the cabinet 99, but in this case the tube is inverted with respect to Figure 1 so that the end containing the cathode is uppermost and the end containing the output target is directed downwardly. The telescoping casing 33, 37 with the outlet conductors 53 and tuning mechanism 55 are shown as in Figure 1, and indeed 20 the arrangement only differs from that figure in details; for example, the tubular rod 12 and the sleeve 39 are lengthened so that the tuning handle 49 can be located outside the cabinet 99. The sleeve 39 in fact passes through the bottom 25 of the cabinet by way of an insulating bushing 39a. The discharge tube itself is fitted with fins 85 similar to those shown in Figure 3, but they are in contact with the condenser plate 30 in which the sub-anode SA is clamped. The cooling 30 of the target end of the tube is effected in this case by allowing air to enter the casing 33, 37 through inlet pipes 121, as shown by arrows 122. These pipes 121 are brought through the deck 83 and communicate with the inside of the casing 33. The upper end of the discharge tube with the lead-in wires for the other electrodes is, as shown at the top of Figure 6, located in the surrounding air. The tubular rod 12 is connected at its lower end to a tube 116 outside the cabinet 99 and connected to the fan 117 driven by the electric motor 118 by an internal pipe 123. Thus, the fan 117 draws in air as shown by the arrows 122, which flows into the casing 33, 37 in contact with the target through the tubular conductor rod 12 by way of the tube 116 and pipe 123, and out through the fan 117. In order to cool the outside of the casing 33, 37, air is drawn in through the deck 83 around the tube itself, as shown by the arrows 124. This relatively slow 35 stream of air is drawn out from the cabinet 99 by the fan 119 driven by the electric motor 120.

I claim:

1. An electron discharge tube installation comprising a metal platform support, an electron discharge tube having a plurality of electrodes including an electrode extending outside the envelope of said tube where same is in contact with said support, a layer of di-electric material in contact with said platform support, a metal plate spaced from said platform by said di-electric material, a metallic casing enclosing at least part of said discharge tube and secured to said metal plate and electrically connected to a further electrode of said tube and formed with inlet and outlet apertures for cooling fluid and means connected to said outlet aperture for passing a stream of cooling fluid through said casing into contact with a part of said tube which is heated in operation.
2. An electron discharge tube installation com-

prising an electron discharge tube having an electrode extending outside the envelope of said tube, a metal partition in contact with and supporting said electrode outside the envelope of said tube, a layer of di-electric material covering a surface of said partition, a metal plate spaced from said partition by said di-electric material, a metallic casing enclosing said tube and divided by said partition electrically and mechanically into two parts connected respectively to input and output electrodes of said tube and secured respectively to said partition and said metal plate, each being provided with inlet and outlet apertures for cooling fluid and means connected to said outlet apertures for passing a stream of cooling fluid through the parts of said casing to serve as a cooling medium for said discharge tube.

3. An electron discharge tube installation comprising a metal support, an electron discharge tube having an electrode extending outside the tube and secured to said support, an enclosing metallic casing secured to said support but spaced therefrom by dielectric material, and connected electrically to a further electrode of said tube to form a part of a circuit thereof, an outer containing housing having an upper wall or deck formed with an air inlet aperture and bearing said casing and electron discharge tube with at least part of said casing enclosed in said housing, means connected to said metallic casing for passing a stream of air through said casing into contact with a part of said electron discharge tube and means connected with the interior of said housing for passing a stream of air into said housing for cooling the external surface of said metallic casing.

4. An electron discharge tube installation comprising an electron discharge tube having an electrode extending outside of the tube, a metal partition to which said electrode is secured, a metallic casing enclosing said discharge tube and divided by said partition into two parts connected respectively to input and output electrodes of said tube, one of said parts being secured to said partition and the other being spaced therefrom by dielectric material, an outer containing housing having an upper wall or deck formed with an air inlet aperture and bearing said casing and electron discharge tube with one part of said metallic casing enclosed in said housing, means connected to said casing for passing streams of air through the parts of said metallic casing to cool said discharge tube and means connected with the interior of said housing for passing a stream of air into said housing for cooling the external surface of the part of said metallic casing within said housing.

5. An electron discharge tube installation comprising a metal support, an electron discharge tube having a plurality of electrodes including an electrode extending outside the tube and secured to said support and provided with heat-radiating fins externally of said tube, a metallic casing enclosing at least part of said tube and electrically connected to a further electrode thereof, said casing being secured to said support but electrically insulated therefrom, means for passing cooling fluid through said casing into contact with a part of said tube which is heated in operation, a housing enclosing said fins at least in part, and means for passing cooling fluid through said housing to abstract heat from said fins.

6. An electron discharge tube installation comprising a metal support, an electron discharge tube having a plurality of electrodes including an electrode extending outside the tube and secured to said support and provided with heat-radiating fins externally of the tube, a metallic casing enclosing said tube and comprising two parts electrically connected respectively to input and output electrodes of said tube, one of said parts being secured to said support and the other being electrically insulated therefrom, means for passing cooling fluid through said parts into contact with portions of said tube which are heated in operation, a housing enclosing said fins at least in part, and means for passing cooling fluid through said housing to abstract heat from said fins.

7. An electron discharge tube installation comprising a metal support, an electron discharge tube having a plurality of electrodes including an electrode extending outside the tube and secured to said support, a metallic casing enclosing at least part of said tube, said casing comprising telescoping sections one secured to said support but electrically insulated therefrom and the other connected electrically to another electrode of said tube to form part of a shielded circuit for said tube, adjusting means for effecting relative sliding of said telescoping parts to adjust the resonant frequency of said shielded circuit, and means for passing cooling fluid through said casing into contact with part of said tube which is heated in operation.

8. An electron discharge tube installation comprising a metal support, an electron discharge tube having a plurality of electrodes including an electrode extending outside the tube and secured to said support, a metallic casing enclosing said tube and comprising two parts electrically connected respectively to input and output electrodes of said tube, one of said parts being secured to said support and the other part comprising telescoping sections one of which is electrically insulated from said support and the other of which is connected to a tube electrode to form part of a shielded circuit of said tube, adjusting means for effecting relative sliding of said telescoping parts to adjust the resonant frequency of said shielded circuit, and means for passing cooling fluid through said casing parts into contact with portions of said tube which are heated in operation.

9. An electron discharge tube installation comprising a metal support, an electron discharge tube having a plurality of electrodes including an electrode extending outside the tube and secured to said support, a metallic casing enclosing said tube and comprising two parts, one connected to an output electrode of said tube and secured to said support but electrically insulated therefrom, the other secured to said support and connected electrically to an electrode of said tube to form a part of a shielded input circuit, a pair of Lecher conductors connected to input electrodes of said tube, a member disposed to bridge said conductors and slidably mounted in said second casing part, adjusting mechanism for effecting sliding movement of said member to adjust the resonant frequency of said input circuit, and means for passing cooling fluid through said casing parts into contact with portions of said tube which are heated in operation.
